TIMING DEVICE

Jesse J. Brown, Syracuse, N. Y.

Application March 26, 1934, Serial No. 717,333

7 Claims. (Cl. 200—34)

The present invention relates broadly to a timing device and more specifically to an electrical timing switch.

It comprises a device for timing the operation of a mechanism, for example, a photographic printer, in such manner that the printer may be controlled to be operative for a given time interval and also wherein the device may be easily rendered ineffective, so that its effective operation may be delayed under the will of an operator whenever it is desirable to retain an intermediate control for a substantial period of time.

The specific embodiment herein disclosed of the present invention is an electrically controlled time switch for a printer for photographic purposes. In making prints or enlargements of photographs, it is desirable to control the effective time when the printing light is operative upon the sensitized paper or other printing medium on which the photograph is being printed. In the commercial printing of photographs where time of operation controls the speed of production, it is desirable that the photograph be printed within a few seconds, which means that the tolerances as to time of printing light are narrow, assuming, of course, that the source of light is of substantially constant intensity, that is, a fraction of a second variation may mean an under-exposed or an over-exposed print, as the case may be.

The preferred embodiment of the present invention comprises a fluid filled cylinder through which a weighted piston is adapted to be moved by gravity. The embodiment herewith, as will be hereinafter described in detail by reference to the drawings, comprises a symmetric apparatus with both ends of the cylinder effective for the purposes desired. There is an electric switch at each end of the cylinder. These switches are connected in series so that the opening of either switch breaks the circuit. Assuming the weighted piston to be at one end of the cylinder and the cylinder to be inverted, the weight of the piston will be supported by the fluid in the cylinder confined beneath the piston. The release of the fluid beneath the piston will control the rate of fall of the piston. This confined fluid may be bypassed relative to the piston in such manner as to be permitted to flow from beneath the piston to a space above the piston. The by-pass is controlled by a suitable adjustable valve so that the rate of release of the fluid beneath the descending piston, is controlled, thereby determining the time interval for the piston to descend the length of the cylinder. This by-pass construction,

whereby fluid is by-passed from one side of the piston to the other, provides a self-contained device in which a suitable fluid may be sealed to insure against loss, and to prevent contamination from dust and dirt. Any gas or liquid which does not vary a substantial amount in viscosity at normal room temperature variations is best suited for the present invention. When the piston reaches the lower limit of its travel, the weight of the piston operates, in the specific embodiment herewith, an electrical switch which opens a circuit and thereby cuts off the printing light.

In the specific embodiment herewith, the cylinder is mounted upon trunnions and is adapted to be oscillated relative to its longitudinal axis, so that the cylinder may alternately be inverted end for end. The control valve in the by-pass is set so that the time interval of the travel of the piston from one end of the cylinder to the other corresponds to the time a proper printing light is effective to properly expose a suitable sensitized paper or other medium through a predetermined negative. When the paper and negative are properly assembled in a suitable printing apparatus, the operator inverts the cylinder. The piston which has been resting on the bottom of the cylinder is now at the top and starts to descend, thereby permitting the switch to close the light circuit. When the piston has descended to the bottom of its travel, the piston opens the electrical switch which is now at the bottom of the cylinder and the printing light is cut off. The operator replaces the exposed sensitive paper with a fresh unexposed sheet and again inverts the cylinder. The piston again travels downward under the influence of gravity and as soon as the weight of the piston is released from the switch which it has opened, this switch closes, thereby lighting the printing light. This light stays lighted until the piston has descended sufficiently to operate the other switch at the now lower end of the cylinder. These operations are continued until the desired number of prints are made when the next negative is tested as to density. The control valve may be reset accordingly and the operations are repeated. The cylinder may be held in a horizontal position to retain the light lighted whenever this is desirable.

While the present invention is adapted to and is explained with reference to its operation in connection with photographic apparatus, it is to be understood that the invention may be useful for other timing operations.

It is recognized that the present invention may be embodied in structures differing from those

specifically disclosed herewith, and, therefore, it is desired that the disclosure herewith shall be understood as illustrative and not in the limiting sense.

5 Fig. 1 illustrates a section of the device on line 1—1 of Fig. 3.

Fig. 2 illustrates a section of the device on line 2—2 of Fig. 3.

10 Fig. 3 shows a section of the device on line 3—3 of Fig. 2.

Fig. 4 shows a diagrammatic illustration of the device as applied to a light adapted for photographic printing.

15 Fig. 5 illustrates a mechanism for oscillating the device by a foot pedal.

Referring to the drawings and more especially to Fig. 1, the device comprises a body portion 1 having a cylindrical bore 2 with a tubular passageway 4 in communication with the cylindrical bore 2 by means of ports 5 and 6. A weighted piston 7 substantially fitting the cylindrical bore 2 is adapted to travel lengthwise therein under the influence of gravity when the body portion of the cylinder is inclined sufficiently toward the vertical to cause gravity to overcome friction of the piston 7 on the side wall of the cylindrical bore 2. The ends of the cylindrical bore are closed by end plates 8. Preferably, the body portion 1 and the end plates 8 are formed of materials capable of being joined together in such manner as to provide a hermetic seal and in the present case, the body portion 1 and the end plates 8 are of metal and the entire outside joint between the end of the body portion and the end plates 8 is closed or sealed by welding as at 9. This obviates any possibility of the escape of the liquid 10 by evaporation or otherwise. This preferably comprises an oil or other fluid which is not subject to substantial expansion or contraction within normal atmospheric temperature ranges and which does not substantially change in viscosity with such temperature changes. Each end plate 8 carries thereon a sylphon member 11. The sylphons are united to the end plates in such manner as to form a hermetic seal and in the present case, the sylphons preferably are of metal and are welded to the metal end plates 8. The sylphons 11 allow expansion and contraction of the fluid due to temperature changes. The sylphons also comprise devices by which terminal movements of the piston 7 may be communicated to an operating part such as an electrical switch. Cap members 12 are mounted upon the end plates 8 by suitable stub screws 14 or other convenient uniting members and these cap members may carry electrical switches 15. Preferably, coil springs 16 extend between the cap members 12 and the ends of the sylphons 11 to assist the movement of the sylphons away from the operating members 17 of the switches 15 when not being weighted down by the pistons. In order that trapped air may not interfere with the free operation of the sylphon members, ports 18 may be provided through the cap members 12. A conduit 19 is provided for suitable electrical connections to the electrical switches 15. Preferably, the body member is provided at its central portion with a pair of oppositely disposed trunnions 20 and 21. The trunnion 21 preferably is provided with an opening 22 leading to the conduit 19 to provide an outlet for the electrical wires leading to the switches 15 so that these wires may be connected with a suitable electrical circuit 24 which is under control of the switches 15.

75 The electric circuit 24 may include an electric

lamp 25 and the circuit is supplied with current by a suitable source of electrical energy. This electrical lamp 25 is the operating lamp for a photographic printed 26. Photographic printers are well known in the art, and, therefore, for purposes of simplification, the photographic printer 26 is merely illustrated diagrammatically.

5 The tubular passageway comprising the by-pass 4 is controlled by an adjustable valve. This adjustable valve may comprise a valve head 27 of 10 sufficient size to completely block the passageway 4 and to be provided with a valve seat 28 so that the passageway 4 is entirely closed when the valve head is completely seated. The valve head carries a threaded extension 29 upon which 15 is mounted an adjustment nut 30 which bears against a valve casing 31. A metallic sylphon 32 is hermetically sealed to the valve head 27 and is also hermetically sealed to the valve casing 31 as for example, by welding. A coiled spring 34 20 normally urges the valve head 27 toward the valve seat 28. This action of the spring 34 is resisted by adjustment of the adjustment nut on the threaded extension 29 so that the valve may be set at any predetermined degree of opening. The 25 valve casing 31 is hermetically sealed to the body portion 1 of the cylinder as by welding as at 35. This construction of the valve is such that no leakage of liquid is possible through the valve casing to the exterior of the parts. In order to obviate any difficulty in operating the valve due to possible leakage around the valve head 27 into the casing 31, a small port opening 36 is provided between the space in the casing 31 and the 35 by-pass 4.

The device may be mounted in different ways for operation, but preferably, is mounted in accordance with the illustration in Fig. 5 wherein the trunnions 20 and 21 are mounted to oscillate in bearing brackets 37. A link 38 may be pivoted 40 to the boss 39 (Fig. 2) on the body portion 1 and is connected at the other end with the vertical arm of a bell crank 40 mounted to oscillate in a frame bracket 41. An adjustable stop 42 adjusts the limit of movement of the bell crank 40 in one 45 direction so that when the lower arm of the bell crank 40 is in contact with the stop, the position of the parts will be such as to maintain the body portion 1 of the cylinder with the longitudinal axis thereof substantially vertical. A pedal 44 50 mounted on a pedal bracket 45 is connected by a link 46 with a horizontal arm of the bell crank 40. A spring 47 normally maintains the forward end of the pedal raised and the lower arm of the bell crank in contact with the adjustable stop 42. 55 A pivoted latch 48 may be provided in front of the pedal so that it may be moved forward as the operator desires to hold the pedal in its lower position whenever this is desirable.

The operation of these parts is such that when 60 the pedal 44 is depressed, the link 38 pulls forward, thereby swinging the cylinder on the trunnions and the momentum of the swinging movement carries the cylinder beyond dead center, so that when the pedal rises, the boss 39 swings 65 to the position 49 indicated in dotted lines in Fig. 5, and the lower arm of the bell crank 40 comes into contact with the adjustable stop 42 leaving the cylinder in inverted position. The piston descends under the influence of gravity and displaces the fluid beneath the piston. The displaced fluid re-enters the chamber above the piston. The rate or speed of descent of the piston through a portion of its travel is determined by the setting of the control valve. A succeeding 75

pressure on the pedal and release thereof causes the cylinder to turn end for end to the position shown in full lines in Fig. 5. Thus, it will be seen that by depressing the pedal and releasing the same the cylinder may be successively inverted end for end. Where it is desirable that the light be retained on continuously for a substantial length of time, the pedal is pushed down and pivoted latch 48 is moved over the end of the 10 pedal, thereby latching it in its lower position. When this happens, the cylinder will assume an inclined position as indicated by the dotted line 50 in Fig. 5.

When the cylinder is inclined, the weight of the 15 piston is removed from the sylphon with which the piston has been in engagement and the spring 16 expands the sylphon to allow the switch 15 to close. While the inclination need be only slightly beyond the horizontal, it should be sufficient to allow the release of the weight from the sylphon, and should be enough to insure that the effect of gravity on the piston is in the direction to tend to move the piston away from the sylphon, but not enough to cause the piston to 25 move under influence of gravity alone.

When the cylinder is in this inclined position, the switches at both ends of the cylinder are closed and the light may be retained lighted so long as the cylinder is held in this inclined position. When it is desired that operations shall 30 be resumed, the latch 48 is released and the cylinder will assume a vertical position as indicated in full lines in Fig. 5.

When the cylinder is in vertical position with 35 the piston in the upper end of the cylinder, gravity operating on the piston causes the same to descend. By reference to Figs. 1 and 2, it will be noted that ports 6-6 are located adjacent the ends of the cylindrical bore beyond the path of movement of the piston 7, while ports 5-5 are 40 located within the path of movement of the piston. When the piston first starts to descend, no substantial retarding action occurs because the fluid is freely by-passed through the ports 5 and 6 45 adjacent the upper end of the cylinder. This permits the piston to move quickly away from the upper sylphon and permits the upper switch to close. Since the lower switch is already closed, the circuit is now completed. As the piston moves downward, it closes the upper port 5, 50 whereby fluid beneath the piston must now be by-passed through the control valve 27 and the travel of the piston is thereby retarded in accordance with the setting of this valve, until the piston has descended sufficiently to open the lower port 5, 55 at which time the fluid beneath the piston is by-passed rapidly from the lower port 6 through the lower port 5 which is now above the piston, and the piston has reached the position indicated in 60 Figs. 1 and 2. The arrangement of the ports 5 and 6 eliminates further retarding action by the valve 27 and permits the piston to move quickly toward the lower end of the cylinder, thereby exerting the full weight of the piston on the lower 65 sylphon and switch mechanism to quickly open the switch 15 in the lower end of the cylinder.

The ports 5-5 and 6-6 should each be at 70 least of the same capacity as the conduit 4. By this arrangement, it will be observed that during the initial and final travel of the piston, it is not substantially retarded in its movement, but as quickly as the piston closes the upper port 5, the further movement of the piston is under control of the control valve 27, until the piston has descended sufficiently to open the lower port 5 at 75

which time the travel of the piston is again independent of the control valve 27. The piston 7 is in effect a movable wall dividing the cylinder into two chambers, one of which contains fluid under slight compression when the weight of the 5 piston is supported by the said fluid.

It will be observed that the present device depends for its timing features upon fluid flow and is, therefore, independent of mechanical clock mechanism or of electrical circuit characteristics, 10 and consequently may be operated in connection with any type of electrical circuit either alternating or direct current. The present device provides a simple and efficient timing mechanism for the purposes intended. 15

What is claimed is:

1. A device of the class described comprising a hermetically sealed cylinder, a piston movable by gravity within said cylinder, sylphon members hermetically sealed to the end walls of said cylinder and being adapted to be collapsed by the weight of said piston, electrical switches operated by said sylphons, and means to control the speed of movement of said piston relative to said cylinder. 25

2. A hermetically sealed cylinder, a piston movable within said cylinder, sylphons hermetically sealed to the end walls of said cylinder, a by-pass connected with the ends of said cylinder, said cylinder being filled with a fluid, said fluid being 30 adapted to flow through said by-pass when said piston moves within said cylinder, a valve for controlling the rate of flow of fluid through said by-pass, said valve being operatively connected to a hermetically sealed sylphon, electrical switches 35 mounted within the sylphons carried by the end walls of the cylinder, and means for oscillating said cylinder to cause the said piston to move therein.

3. A device of the class described, a chamber, 40 a piston slidable in said chamber, said chamber containing a fluid, a conduit in communication with both sides of said piston whereby the movement of the piston displaces fluid from one side of the piston and replaces the fluid on the 45 opposite side thereof, control means for regulating the rate of flow of said fluid through said conduit, and relief ports connecting said chamber with said conduit so as to render said control means ineffective when the piston passes a pre-determined point in the chamber. 50

4. A hermetically sealed cylinder, a piston movable by gravity within said cylinder, bellows or diaphragms hermetically sealed into the ends of said cylinder and adapted to having motion imparted thereto by the movement of said piston, a by-pass connecting the ends of the cylinder, said cylinder being filled with a fluid, said fluid being adapted to flow thru said by-pass when said piston moves within said cylinder, a control valve 55 for regulating the rate of flow of said fluid thru the by-pass, said control valve being operatively connected to a hermetically sealed bellows or diaphragm, electrical switches adapted to be operated by the movement of the first-mentioned bellows or diaphragms when same are actuated by the movement of the piston, and relief ports connecting said cylinder with said by-pass, said relief ports being so located in relation to the travel of the piston and in relation to the location of the said control valve that the fluid below the piston is freely by-passed thru the nearest relief port to the space above the piston independent of the action of the said control valve at 60 65 70 75

a time just prior to the piston reaching the end of its travel.

5. A hermetically sealed cylinder, a piston movable by gravity within said cylinder, bellows or diaphragms hermetically sealed into the ends of said cylinder and adapted to having motion imparted thereto by the movement of said piston, a by-pass connecting the ends of the cylinder, said cylinder being filled with a fluid, said fluid being adapted to flow thru said by-pass when said piston moves within said cylinder, a control valve for regulating the rate of flow of said fluid thru the by-pass, said control valve being operatively connected to a hermetically sealed bellows or diaphragm, and electrical switches adapted to be operated by the movement of the first-mentioned bellows or diaphragms when same are actuated by the movement of the piston.

10. A hermetically sealed cylinder, a piston movable by gravity within said cylinder, bellows or diaphragms hermetically sealed into the ends of

said cylinder and adapted to having motion imparted thereto by the movement of said piston, a by-pass connecting the ends of the cylinder, said cylinder being filled with a fluid, said fluid being adapted to flow thru said by-pass when said piston moves within said cylinder, and a control valve for regulating the rate of flow of said fluid thru the by-pass, said control valve being operatively connected to a hermetically sealed bellows or diaphragm.

15. A hermetically sealed cylinder, a piston movable by gravity within said cylinder, bellows or diaphragms hermetically sealed into the ends of said cylinder and adapted to having motion imparted thereto by the movement of said piston, a by-pass connecting the ends of the cylinder, said cylinder being filled with a fluid, and said fluid being adapted to flow through said by-pass when said piston moves within said cylinder.
